UNITED STATES PATENT OFFICE.

CHARLES E. WEHN, OF ALAMEDA, CALIFORNIA.

PENCIL LEAD.

1,411,822.

Specification of Letters Patent.

Patented Apr. 4, 1922.

No Drawing.

Application filed February 24, 1920. Serial No. 360,963.

To all whom it may concern:

Be it known that I, CHARLES E. WEHN, a citizen of the United States, residing at Alameda, in the county of Alameda and State 5 of California, have invented a new and useful Improvement in Pencil Leads, of which the following is a specification.

This invention relates to pencil leads and the means of adapting them to fit into and 10 be held in pencil holders of the character in which the lead is fed forward for use as desired. More particularly the invention pertains to a means whereby the diameter 15 of leads and the like may be slightly increased by the application of a semi-hard coating material and a frictional resistance produced.

Ordinary pencil leads in use today consist 20 of a composition of graphite, paraffine, clay or similar earthy substances. These ingredients are finely ground and thoroughly mixed in certain proportions, the proportions employed depending of course upon the degree of hardness or color desired. A 25 dough-like material is in this manner formed which is passed through molds or dies of uniform diameter and is in this manner reduced to the desired shape and diameter. The molded material is next dried and is 30 then placed in ovens where the leads are baked under high temperature for a considerable time period. The leads are finally removed and cooled and the manufacturing operation may in this instance be considered 35 completed.

Minute examination of the leads, whether 40 of one composition or another will show a considerable variation in exterior diameter and the cause of this variation may be traced to different sources, for instance, some manufacturers mold the leads by passing the dough-like composition under high pressure through a die. This die is subject 45 to considerable wear and the diameter of the leads is thus gradually increased until the increase is so great that renewal of the die is necessitated. Again shrinkage takes place during the drying and baking operation, and the shrinkage of course varies 50 with the composition. Hence it is found in actual practice that the leads vary from two to three thousandths of an inch in diameter and a uniform product cannot be obtained except by the grading of leads when 55 completed. This variation as previously stated is slight and is neither noticeable nor

detrimental when the leads are cemented and permanently incased by wood, as in ordinary pencils, but it presents an entirely different problem when the leads are placed 60 in what may be termed mechanical or refillable pencils of different makes. Pencils of this character are usually provided with a lead holder in which is formed a lead receiving passage and a feed mechanism where- 65 by the lead is gradually advanced when worn. The leads in certain forms of pencil are held in the holder or receiving passage solely by snug fit or frictional engagement, while other makes of pencils are provided 70 with mechanisms for increasing or decreasing the diameter of the lead receiving passage, or for clamping the leads therein, such mechanism being provided with no other object in view than that of taking 75 care of the slight variation of the exterior diameter of the leads. Most pencils of the character described are however provided with a non-contracting lead receiving passage of uniform diameter and any decrease 80 in diameter, even though it be only one or two thousandths of an inch, renders the pencil inoperable as the leads cannot be retained and will therefore fall out.

The purpose of the present invention is 85 to overcome the above objections, for instance, the elimination of mechanical means for increasing or decreasing the diameter of the lead receiving passage or of providing means for clamping the leads therein, 90 and further eliminates the necessity of grading, the main object being to always insure a snug fit and to produce a frictional resistance of the leads in the holders whether the diameter is under or above size. This 95 is accomplished by coating the leads with a semi-hard substance such as wax, paraffine and the like. This coating material is applied in any suitable manner, for instance, by dipping the leads in paraffine. The ma- 100 terial when hardened presents a semi-hard friction producing coating which slightly increases the diameter of the leads, that is at least to such an extent that a snug fit will be formed between the leads and the 105 holder in which they are inserted regardless of whether the leads were originally too small.

An important feature of the present invention is the use of a coating material 110 which is semi-hard when dried or set as it permits use of all leads whether under-

size or of proper diameter, for instance, if a coated lead of proper diameter is inserted, it is obvious that the coating material, due to its semi-hard nature will be scraped off 5 or removed when the lead is inserted, similarly that the coating on leads of smaller diameter may be only partially removed and in extreme instances not removed, the thickness of the coating material being such that 10 it will form a filler between the interior surface of the lead receiving passage and the lead proper and is under all conditions so soft that any excess material is easily removed when the leads are inserted. A snug 15 fit is in this manner obtained whether the leads are oversize or undersize and a frictional resistance is produced, thus mechanical contrivances for securing the leads will therefore be entirely eliminated. The cost 20 of manufacture is in this manner reduced and a simple and easily operable pencil becomes possible.

For the purpose of this specification, it is assumed that the apertures of mechanical 25 pencils or the holders which are to receive the lead are of substantially uniform diam-

eter, while the leads, as above described, are of non-uniform diameters. Therefore the invention is the adaptation of means whereby leads of non-uniform diameters are 30 brought to uniformity. In carrying out this object it is preferable to build up the undersized non-uniform leads to oversize by the medium of a skin covering which is not only softer than the lead but has sufficient 35 inherent rigidity or hardness and sufficient permanence that it is readily reduced to the desired size under conditions of actual use in the holder.

Having thus described my invention, what 40 I claim and desire to secure by Letters Patent is—

An article of manufacture consisting of 45 pencil leads having an exterior coating of paraffine.

In testimony whereof I have hereunto set my hand in the presence of two subscribing witnesses.

CHARLES E. WEHN.
